to Scovill Manufacturing Company, Waterbury,
Conn., a corporation of Connecticut

Application May 31, 1946, Serial No. 673,548

6 Claims. (Cl. 128—200)

1

This application is a continuation in part of my copending application, now abandoned, Serial No. 577,650, filed May 13, 1945.

This invention relates to inhalers and particularly to pocket inhalers of the type in which there is a medicated filler adapted to produce vapors for treatment of the air passages of the nose, throat and lungs.

Devices of this character are frequently provided with a nozzle designed to be applied directly to the user's nostril so that air may be drawn through the container and over the filler to carry vapors into the nose and throat. However, such structures have not always been provided with sufficient air passages to permit air to be drawn through the device readily and in some instances the openings through which air passes into the device have been so located as to be obstructed or covered by the fingers or when held to the nostril for use. Moreover, since the medicinal material used is necessary volatile, it is important to provide means for adequately sealing the device when not in use. It is also necessary for such devices to be inexpensive and simple in construction since they are discarded when the filler has become exhausted or has lost its effectiveness.

In accordance with the present invention, constructions which overcome these objections and limitations of prior inhalers are provided by forming the device of simple elements which are limited in number and inexpensive to produce and assemble. The construction embodies telescoping elements which include an outer casing and a nozzle or nostril engaging member that is normally housed within the casing but is movable to a projected position when in use. The parts are also formed to afford ample air passages for flow of air through the device and the construction further is provided with means whereby both the casing and the nozzle may be sealed to prevent evaporation or loss in effectiveness of the medicament employed.

One of the objects of the present invention is to provide a novel type of pocket inhaler which is simple and economical to manufacture and assemble and easy and effective to use.

Another object of the invention is to provide improved sealing means whereby waste of the medicinal value of the filler is avoided and leakage of the volatile constituents to the outside of the casing when the device is not in use is precluded.

Another object of the invention is to provide an inhaler of improved simple and economic con-

2

struction in which the inhalator nozzle is movable within an outer casing so that the aperture of the nozzle may be conveniently applied to the nostril without contact with the external casing.

5 A further object of the invention is to provide new and improved guiding means for the telescoping members of such devices so that alignment of the parts is at all times insured and jamming or tilting of the parts during movement is prevented.

10 A still further object of the invention is to provide an inhalator of the type set forth which is of improved efficiency providing for free and unencumbered air admitting passages as well as a free passage for air over the medicament and 15 through the nozzle orifice.

These and other objects and advantages of the present invention will be apparent from the following description thereof in which reference is made to the accompanying drawings.

20 In the drawings:

Fig. 1 is a side elevation partly in section showing one embodiment of the invention with the cap in position;

Fig. 2 is a horizontal sectional view of the construction shown in Fig. 1 taken on the line 2—2 thereof;

Fig. 3 is a side elevation of the construction shown in Fig. 1 with the cap removed and the nozzle of the holder projected;

30 Fig. 4 shows an exploded view of the several parts of the inhaler shown in Fig. 1 as they appear before assembly;

Fig. 5 is a view partly in elevation and partly in section showing the outer casing of the construction illustrated in Fig. 1;

Fig. 6 is a side elevation partly in section of an alternative embodiment of the present invention;

Fig. 7 is a horizontal sectional view of the construction shown in Fig. 6 taken on the line 7—7 thereof;

Fig. 8 is an exploded view of the construction shown in Fig. 6 with the several parts as they appear before assembly;

Fig. 9 is a side elevation partly in section of another alternative form of my device; and

Fig. 10 is an exploded view of the construction shown in Fig. 9 with the several parts as they appear before assembly.

Referring to that form of the invention shown 50 in Figs. 1 to 5 of the drawings it will be seen that the construction embodies an outer generally cylindrical casing or shell 2, and an inner open ended medicament holder 4 which is slidably fitted in the shell 2 and urged outwardly toward a projected position by a spring 6. The holder is

designed to receive and retain an absorbent material which may be saturated with the inhalant or the material may be in the form of crystals or of any other preferred type but is not illustrated in the drawings.

A cap 8 is adapted to be applied to the open upper end of the casing 2 and engages the upper nozzle end of the holder 4 to depress the holder against the action of spring 6 so as to hold it in a retracted position when the cover is secured in place. The cap 8 preferably is formed of relatively light, thin and inexpensive material and comprises a head 10, the side edges of which are knurled as shown at 12 to provide a convenient gripping surface. Located within the cap 8 is a suitable sealing member 14 which may be of cork, rubber or other conventional sealing material.

The skirt of the cap 8 is provided with threads 15 for engagement with external threads 16 on the upper end of the outer casing 2. The upper, or cap receiving portion of the casing 2, is of smaller diameter than the main portion 20, and a shoulder 22 is formed at the place of union of the two portions which serves as an abutment for the lower edge of the cap to limit its downward motion on the casing. However, in most instances it is preferable to permit the sealing member 14 within the cap to limit movement of the cap toward the container since it is then possible to assure a tight seal of the cap about the upper open end of the casing.

When the cap 8 is in position on the end of the casing 2 it not only seals the open end of the casing and retains the holder in a retracted position, but also engages the nozzle 24 on the outer end of the medicament holder 4 and serves to close and seal the central opening 26 in the nozzle to provide a separate and effective seal for the nozzle as well as the casing itself.

The open upper end of the casing 2 is provided with an inturned mouth flange 28 which presents a smooth and finished appearance to the open end of the casing, insuring the user against accident caused by sharp or rough edges. This flange also serves to limit outward movement of the holder 4 under the action of spring 6. The lower or bottom end of the casing is closed by a conventional end wall 30.

Telescopically mounted within the external casing or shell 2 is the open ended cylindrical holder 4. The upper end of the holder is formed with the tapered nostril engaging portion or nozzle 24 having the central opening 26 therein. The material about the opening 26 is drifted inward as shown at 32 so that the end surface of the nozzle is smooth and free from exposed rough edges which might engage the nostril and the surface is flat and positioned at right angles to the axis of the holder 4 so as to present a sealable surface which may be engaged by the sealing member 14. With this construction both the nozzle and the open end of the external casing may be simultaneously sealed by the sealing member 14, carried by cap 8.

In order to provide adequate channels for the flow of air into and through the casing and holder, the holder 4 is provided with a plurality of circumferentially spaced vent grooves 34 which extend from a point below the beginning of the tapered nozzle 24 to a point at or below the center of the holder. These grooves project inwardly on the holder and are of such length as to provide plurality of air passages which extend from the exterior of the casing past the flange 28 at the

upper end of the casing to the interior thereof when the holder is projected to its operative position as shown in Fig. 3. The vent grooves 34 are thus positioned so that they will not be obstructed by the fingers or nose even if the nozzle is inserted well into the user's nostril. The grooves also extend into the outer casing below the flange 28 a distance sufficient to insure free flow of air into and through the casing to the opening 36 at the lower end of the holder. From the opening 36 the air flows upward through the holder 4 to the opening 26 in the nozzle 24. In this way large and unobstructed passages are provided so that the user may draw vapors through the inhaler without effort.

The walls of the holder 4 below the nozzle 24 are also provided with guide ribs 38 which are preferably spaced circumferentially so as to be located between the vent grooves 34. The ribs 38 project outwardly from the holder and extend longitudinally thereof terminating at their upper ends in shoulders 40 which are designed to engage the inwardly extending flange 28 on the upper end of the casing 2 to limit outward movement of the holder under the action of the spring 6.

The side faces of the ribs 38 present smooth bearing and guiding surfaces engagable with the internal surface of the casing 2. The ribs thus provide extended and spaced supports for the holder which insure smooth straight and rectilinear movement of the holder and prevent tilting or jamming thereof within the outer casing.

The shoulders 40 are located below or spaced downwardly from the upper ends of the vent grooves 34, and therefore when the holder is in its projected position the vent grooves 34 extend from points above the flange 28 to points below this flange and permit air to flow freely inwardly past the flange 28 to the space between the casing and the holder and to the opening 36 in the lower end of the holder. The air thus entering the outer casing passes upward over or through the medicament or filler within the holder to the opening 26 in the nozzle 24.

The holder 4 is normally urged outwardly toward the projected position shown in Fig. 3 by means of the spring 6. The lowermost turn of the spring 6 is squared and lies flush against the inner surface of the bottom wall 30 of the casing 2. The internal diameter of the spring 6 is slightly greater than the external diameter of the lower portion 42 of the medicament holder 4 and surrounds the lower portion of the holder. The upper end of spring 6 is squared and bears against the downwardly facing shoulder 44 of the guide ribs 38. Thus the spring is so placed as to avoid interference with the contents of the holder, and the use of separate or special members for confining the spring is unnecessary. The construction described is simple and easy to produce and provides for sealing of both the holder and casing when in retracted position. Moreover, the holder is supported and guided in its movement without reducing or limiting the volume of the holder or resorting to additional elements or complicated structure. At the same time the device presents a neat and attractive appearance and is always in a sanitary condition.

That form of the invention shown in Figs. 6 to 8 inclusive is in many respects similar to the device shown in Figs. 1 to 5 inclusive. Like numerals are therefore used for corresponding parts. In this form of the device the outer casing 2 receives the holder 4 which is normally urged toward a project-

ed position by the spring 6. The cap 8 cooperates with the nozzle 24 to seal the outer end of the nozzle and to seal the open end of the casing 2. Vent grooves 34 are also similarly formed in the holder 4, and guide ribs 38 extend from the external surface with upper shoulders 46 formed to engage the inturned flange 28 formed on the outer casing 2.

In this form of the invention, however, the guide ribs 38 extend downwardly from points below upper ends of the vent grooves to the lowermost end of the medicament holder. The holder is thus supported throughout the greater part of its length to further prevent the tilting and jamming of the medicament holder during its movement. Moreover, the spring 6 in this form of my invention, has an external diameter less than the internal diameter of the medicament holders 4, and is located within the holder. The lowermost turn of the spring 6 bears against the inner surface of the end wall 30 and its uppermost turn bears against downwardly facing shoulders 46 formed at the inner ends of the vent grooves 34.

The form of the invention shown in Figs. 9 and 10 is also similar to the one shown in Figs. 1 to 5 inclusive, but in this form of the invention guide ribs 48 between vent grooves 34 are relatively short, and additional guide ribs 50 extend lengthwise of the holder adjacent the lower end thereof. The guide ribs 48 engage the inturned flange 28 on the upper end of the casing 2 when the holder is projected so as to limit the outward movement of the holder whereas the guide ribs 50 terminate at their upper ends in inwardly turned shoulders 52. Within the holder there is mounted an abutment washer 54 more clearly shown in Fig. 10. The external configuration of the washer 54 is substantially the same as the internal configuration of the holder taken at the ribs 50 and is provided with projections 56 which abut shoulders 52 to hold the washer in place and provide a bearing for the upper end of a spring 6 mounted between the washer 54 and the lower end wall 30 of the casing 2.

In this construction the size of the spring need not be so accurately maintained since the washer may be formed to extend further into the holder than the lower ends of the vent groove against which the spring abuts in that form of the invention shown in Figs. 6 to 8. Furthermore, it is not necessary to extend the guiding ribs throughout the length of the holder, since the guide ribs 48 and 50 are spaced sufficiently to provide adequate bearing and support for the holder in its movement within the outer casing.

In each of the forms of the invention described the outer casing, prior to assembly, is completely formed except for the inwardly turned flange 28 at the open upper end of the casing. This flange is not formed until after the elements are assembled and the casing is therefore supplied to those who charge the holder with the medicament with the end thereof extended as shown in dotted lines at 58 in Fig. 5. In assembling the elements the spring 6 is inserted into the outer casing so as to rest against the base 30 of the casing. The holder, charged with vaporizable medicament, is then inserted into the casing 2 so that the spring surrounds the holder and engages the downwardly facing shoulders 46 of the guide ribs as shown in Figs. 1 to 5. When using the construction of Figs. 6 to 8 the spring 6 extends into the interior of the holder and its upper end bears against the inwardly extending downwardly facing shoulder 46 at the lower ends of the vent grooves 34. Simi-

larly in the construction of Figs. 9 and 10 the spring 6 bears against the abutment washer 54 when the parts are assembled.

In each of the constructions shown the holder is depressed after the parts are assembled and the upper end 58 of the casing 2 is spun inward to form the retaining flange 28. The structure is then completed and ready for use and the cap 8 can be applied to the casing to seal the casing and nozzle.

From the foregoing it will be seen that the present invention provides novel and improved venting means to insure a free flow of air through the device and yet embodies a limited number of elements each of which is capable of ready manufacture and assembly. The inhaler further embodies improved sealing and closing means, as well as improved guiding and aligning means which preclude tilting, jamming or misalignment of the parts and insure continuous smooth operation of the device.

While typical and preferred embodiments of the present invention have been illustrated in the drawings and described above, it will be apparent that numerous other changes, modifications and the full use of equivalents may be resorted to in the practice of the invention. In view thereof it should be understood that the constructions shown are intended to be illustrative only and are not intended to limit the scope of the following claims.

I claim:

1. An inhaler comprising a casing, a medicament holder slidably movable within said casing and having a lower portion and a nozzle portion, air channels formed in said holder and positioned extending longitudinally in the lower portion thereof, said holder lying entirely within said casing when in one position to which it is movable, longitudinally extending ribs located between said air channels and projecting outwardly from the exterior surface of said holder to engage said casing and guide the holder on movement thereof, said ribs presenting downwardly facing shoulders on the lowermost ends thereof and spring means engaging said shoulders and casing for moving said holder with respect to said casing to a position in which portions only of said air channels are exposed to the exterior of said casing.

2. An inhaler comprising an open ended casing, a holder movable to a position entirely within said casing and comprising a lower portion and an upper nozzle portion, spring means engaging the end wall of said casing and embracing the lower portion of said holder for urging said holder outwardly from said casing, air conducting passages spaced around the exterior surface of the lower portion of said holder below said nozzle portion, guide ribs located between said air conducting passages so as to engage said casing and extending partially along said holder in a longitudinal direction, said guide ribs being formed with downwardly facing shoulders on their lower extremities for engaging the uppermost turn of said spring means and with upwardly facing shoulders on their uppermost extremities, and means on said casing cooperating with the upwardly facing shoulders on the guide ribs for limiting the outward movement of said holder with respect to the casing the upper portion of said air passages being exposed to the exterior of said open ended casing when said holder is urged upwardly to its uppermost position.

3. An inhaler comprising a casing, a medicament holder having a lower portion and an upper

nozzle portion slidably movable in said casing to a position in which said holder is housed entirely within said casing, depressions in the outer surface of said holder forming air conducting passages extending longitudinally of the lower portion of said holder and located so as to be exposed to the exterior of said casing when the holder is in one position to which it is movable, said air passages being spaced from said nozzle portion, guide ribs on said holder located between said passages and extending longitudinally of the holder, said guide ribs being formed with downwardly facing shoulders at the lower ends thereof and upwardly facing shoulders at the upper ends thereof, spring means engaging the end wall of said casing and embracing the lower portion of said holder with the uppermost turn thereof bearing against said downwardly facing shoulders for urging said holder outwardly from said casing and an inwardly turned flange formed on the casing adjacent the open end thereof for engaging said upwardly facing shoulders to limit outward movement of said holder when the air conducting passages are partially exposed to the exterior of the casing.

4. An inhaler comprising an open ended casing, a holder movable to a position entirely within said casing and having a lower portion and an upper nozzle portion, said nozzle portion being movable through the open end of said casing, said holder having depressions formed in the outer surface of the lower portion thereof providing outwardly facing air channels extending longitudinally of the holder, said depressions extending inwardly from the inner surface of said holder and presenting downwardly facing shoulders at the lower ends of said depressions, spring means bearing against said shoulders and against said casing for urging said nozzle outward through the open end of said casing, and longitudinally extending bearing surfaces on said casing and holder located between said channels for supporting and guiding said holder in its movement relative to said casing.

5. An inhaler comprising an open ended casing, a holder movable to a position entirely within said casing and comprising a lower portion and an upper nozzle portion, spring means engaging the end wall of said casing and embracing the lower portion of said holder, for urging said holder outwardly from said casing, air conducting passages spaced around the exterior surface of the lower portion of said holder and spaced from said nozzle portion, guide ribs located between said air conducting passages so as to engage said casing and extending partially along said holder in a longitudinal direction, said guide ribs being formed with downwardly facing shoulders on their lower

- extremities for engaging the uppermost turn of said spring means and with upwardly facing shoulders on their uppermost extremities, means on said casing cooperating with the upwardly facing shoulders on the guide ribs for limiting the outward movement of said holder with respect to the casing, the upper portion of said air passages being exposed to the exterior of said open ended casing when said holder is urged upwardly to its uppermost position, and a cap for said outer casing, said cap having a sealing disc in the top thereof adapted to tightly engage the end of said nozzle and the open end of said casing when said cap is applied to said casing.
- 5 6. An inhaler comprising a casing, a medicament holder having a lower portion and an upper nozzle portion slidably movable in said casing to a position in which said holder is housed entirely within said casing, depressions in the outer surface of said holder forming air conducting passages extending longitudinally of the lower portion of said holder, said air passages being located so as to be exposed to the exterior of said casing when the holder is in one position to which it is movable, said air passages being spaced from said nozzle portion, guide ribs on said holder located between said passages and extending longitudinally of the holder, said guide ribs being formed with downwardly facing shoulders at the lower ends thereof and upwardly facing shoulders at the upper ends thereof, spring means engaging the end wall of said casing and embracing the lower portion of said holder with the uppermost turn thereof bearing against said downwardly facing shoulders for urging said holder outwardly from said casing, an inwardly turned flange formed on the casing adjacent the open end thereof for engaging said upwardly facing shoulders to limit outward movement of said holder when the air conducting passages are partially exposed to the exterior of the casing, and a cap for said outer casing, said cap having a sealing element located in the top thereof engageable with the end of said nozzle and the end of said casing when said cap is applied to said casing.
- 10 15 20 25 30 35 40 45
